UNITED STATES PATENT OFFICE.

JOHN PLUMMER JACKSON, OF ORLEANS, INDIANA.

ATTACHMENT FOR SPECTACLES.

No. 814,707.

Specification of Letters Patent.

Patented March 13, 1906.

Application filed March 30, 1905, Serial No. 252,899.

To all whom it may concern:

Be it known that I, JOHN PLUMMER JACKSON, a citizen of the United States, residing at Orleans, in the county of Orange and State of Indiana, have invented a new and useful Attachment for Spectacles, of which the following is a specification.

This invention relates to devices of that class known as "grab-fronts" for attachment to ordinary spectacles or eyeglasses.

The principal object of the invention is to provide an auxiliary lens-mounting of simple construction which may be readily attached to or removed from the main lens-supporting frame and which will retain its position by gravity, a further object being to so distribute the weight of the grab-front that the lower portion only of the same will engage with the lower portions of the main lens-carrying rims, so that there will be no danger of scratching either lens.

A still further object of the invention is to provide a device of this character in which the auxiliary lens-supporting rims are arranged at an oblique angle to the general plane of the auxiliary frame, and the auxiliary frame is provided with widened hook members, which will permit the upper portion of the frame to ride out by gravity until the auxiliary lenses assume an oblique angle to the main lenses.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a transverse sectional elevation of a portion of an ordinary pair of spectacles, illustrating the application thereto of a grab-front constructed in accordance with the invention. Fig. 2 is a front elevation illustrating the grab-front in position on the main frame. Fig. 3 is a detail perspective view of the grab-front detached. Figs. 4 and 5 are detail perspective views of portions of the grab-front, the views being on an exaggerated scale. Fig. 6 is a view similar to Fig. 1, illustrating a

modified form of grab-front frame. Fig. 7 is a detail perspective view of the same.

Similar characters of reference are employed to indicate corresponding parts throughout the several figures of the drawings.

In the majority of auxiliary lens-carrying frames, or "grab-fronts," as they are known to the trade, no provision is made for preventing contact between the main and auxiliary lenses or between the frame of the grab-front and the main lens, and this soon results in the scratching of the lenses and necessitates frequent renewal of the same. In carrying out the present invention provision is made for preventing any contact whatever between the lenses or between any one lens and a portion of the frame of the other, so that there can be no scratching of either set of lenses.

In the drawings, *a* designates the lens-supporting rims of the main frame, and *b* the nose-piece thereof. The grab-front forming the subject of the present invention includes a bridge or nose piece, to the opposite ends 80 of which are secured arms 2. The lower ends of the arms are curved to follow the general contour of the lower and inner portions of the main rims *a* and terminate at a point adjacent to the median vertical line of said rims. 75 The upper ends of the arms are upset to form enlargements or lugs 3 for the reception of the securing screw or pin 4 by which the end of the bridge-piece is held to the arm, and each arm is thence bent inwardly and downwardly, forming a hook member of rather extensive width for engagement with the bridge of the main frame. At the end of each of the arms is secured an auxiliary lens-supporting rim 5, containing an auxiliary lens 6. The 90 ends of each rim are provided with ears or lugs 6' of a diameter greater than the width of the rim or the diameter of the arm, and said ears or lugs are provided with threaded 95 perforations for the passage of a clamping-screw 7, by which the rim may be clamped tightly upon the auxiliary lens. 100

The main spectacles are to be worn in the usual manner and generally are intended for distant vision. If the wearer wishes to read 105 or to examine objects close at hand, the grab-front is dropped onto the main frame, it being merely necessary to place the hooks of the grab-front over the end portions of the bridge, the grab-front assuming its position 110

by gravity. It will be observed that when in position on the main frame the ears or lugs 6' make contact with but a small portion of the main rims, and thereby hold the arms of the auxiliary frame outward from the rims and at the same time keep the auxiliary lenses from contact with the main lenses. By bending the auxiliary lens-carrying rims outward at an obtuse angle to the general plane of the arms the center of gravity of the auxiliary rims and lenses is moved outward from the plane of the main lenses in such manner that the ears or lugs 6' will be held by gravity against the main rims, and said ears or lugs will thus form a fulcrum for the movement of the upper portion of the auxiliary frame, so that the latter, being lighter than the auxiliary rims and lenses, will be drawn forward until the rearmost portions of the bills of the hooks engage with the extreme forward portions of the bridge of the spectacles, and this relation will continue so long as the grab-front is in use. The width of the hook is, furthermore, of advantage in that it necessitates no close fitting, and the hook may be readily placed over the bridge without removing the main frame, and there is, furthermore, no necessity of tight clamping of the grab-front to the main frame, as is the case with the majority of grab-fronts now in commercial use.

In Figs. 6 and 7 is shown a grab-front frame of simple construction also embodying the invention. In this case the frame member 2' is made of a single piece having its central portion bent to extend over the nose and provided at its opposite ends with supports for the auxiliary lenses. From the frame member extend the hooks which engage with the frame of the main spectacles. The nose-piece portion of this frame is bent outward approximately in a horizontal plane, and

thus forms a counterweight that will tend to hold the lower portion of the frame in engagement with the rims of the main lenses. 45

Having thus described the invention, what is claimed is—

1. In a grab-front for spectacles or eyeglasses, a frame having wide hooks for loose engagement with the main lens-mounting, and including arms which follow generally the curvature of the inner and lower portions of the main lens-supporting rims, auxiliary lens-supporting rims carried by said arms and bent outward in a plane oblique to the general plane of said arms, said auxiliary rims having enlarged ears or lugs which are forced by gravity against the lower portions of the main rims to form fulcrums for effecting outward movement of the upper portion of the frame with respect to the main lens-mounting. 55

2. In a grab-front for spectacles or eyeglasses, a frame including a pair of curved arms and a nose-piece, a pair of weighted hooks for engagement with the main lens-mounting, auxiliary lens-carrying rims having their lower edges secured to the end portions of the arms, the auxiliary rims being bent outward at an angle oblique to the general plane of the arms, the upper portion of the nose-piece being bent out at an angle to such plane, thereby throwing the center of gravity forward and causing the lower portions of said rims to rest against the lower 70 portions of the main lens-rims. 75

In testimony that I claim the foregoing as my own I have hereto affixed my signature in the presence of two witnesses.

JOHN PLUMMER JACKSON.
